UNITED STATES PATENT OFFICE.

CHRISTIAN NIELSEN, OF ROXBURY, AND CHESTER IRA BABCOCK, OF NEWTONVILLE,
MASSACHUSETTS, ASSIGNORS TO ENSIGN MANUFACTURING COMPANY, OF BOSTON,
MASSACHUSETTS, A CORPORATION OF MASSACHUSETTS.

DRIVE FOR CALCULATING-MACHINES.

1,234,685.

Specification of Letters Patent. Patented July 24, 1917.

Application filed August 5, 1916. Serial No. 113,298.

To all whom it may concern:

Be it known that we, CHRISTIAN NIELSEN, a citizen of the United States, residing at Roxbury, county of Suffolk, State of Massachusetts, and CHESTER IRA BABCOCK, a citizen of the United States, residing at Newtonville, county of Middlesex, State of Massachusetts, have invented an Improvement in Drives for Calculating-Machines, of 10 which the following description, in connection with the accompanying drawing, is a specification, like characters on the drawing representing like parts.

This invention relates to improvements 15 in controlling devices and relates more specifically to a driving mechanism for calculating machines and similar organizations.

It is common at present to employ a 20 spring motor to rotate the meter or indicia-bearing means upon which the numerical results are displayed to the operative as the necessary torque is not readily built up by the small electric motors available for this purpose; and, furthermore, the strain of the 25 constant starting under the maximum load is highly detrimental to this type of power source. Such spring motor is automatically re-wound, when its tension drops below a predetermined point, by the intermediary 30 of an electric motor.

In this improvement an electric motor or other power means is employed, and, during the operation of the calculating machine, the power source runs continuously. The 35 transmission of the power is effected through the interposition of a novel driving mechanism and clutch. It was found undesirable to employ a clutch which throws the power into and out of engagement sharply, as the 40 resultant rebound or jump of the meter or numeral-bearing wheels entails liability to inaccuracies in the arithmetical results. Therefore, there has been produced a drive and transmission which very suddenly accelerates to a direct drive and which, when 45 thrown out of engagement with the power source, effectually prevents back-lash or rebound in the driven members.

An object of this invention is to provide 50 an efficient driving mechanism for calculating machines.

Another object is to provide a drive and clutch mechanism which will obviate the

jump and rebound of the index wheels or meter.

A more specific object is to provide a driving mechanism which actuates the driven member through applying a constant torque thereto, the driven member being intermittently permitted to move to achieve its 60 function.

Other objects of the invention will more 65 fully appear from the following description and the accompanying drawings and will be pointed out in the annexed claims.

In the accompanying drawings, there has been disclosed a structure designed to carry out the objects of the invention, but it is to be understood that the invention is not confined to the exact features shown, as various 70 changes may be made within its reasonable scope.

In the drawings,

Figure 1 is a side elevation of the novel clutch and drive as applied to a calculating 75 machine;

Fig. 2 is a section on the line 2—2 of Fig. 1;

Fig. 3 is a section on the line 3—3 of Fig. 2;

Fig. 4 is a view similar to Fig. 1 of a 80 modification;

Fig. 5 is a view similar to Fig. 1 of another modification.

The selected embodiment of this invention is disclosed in the drawings as having a casing 1. A metallic substance is employed for this purpose in order to effect economy in the space necessarily occupied by the device and aluminum is preferably 90 used as its lightness aids in keeping the weight of the machine as low as is compatible with efficiency and durability.

The shaft 2, which carries the numeral index wheel composing the meter upon which the arithmetical result is suitably displayed to the operative, is journaled in the casing 1. One of the journals is disclosed in section in Fig. 2. They each consist of a standard 3 having an offset portion affording a bearing 100 4 for the shaft 2. The casing 1 has, preferably, similar end slots 5, one being shown in Fig. 2. The slots receive the shaft end portions in the assembling of the incased machine.

The clutch means is disposed between the 105

driving element and the meter in this preferred embodiment. It has been common heretofore to have a clutch or stop-motion at the shaft opposite the drive. Disadvantages in this organization developed in that the whole meter-bearing shaft between the clutch and driving element was subject to torsional displacement due to shaft flexibility and to the inertia or to the momentum of the parts attendant upon sudden starting or stopping. The result was that the meter or index wheels jumped past the correct indications—thus rendering the machine inaccurate. In this structure, the maximum play of any shaft torsional strain is confined substantially to one portion of the shaft, viz., that included between the driven member portion of the clutch and the meter, which two devices are positioned relatively close together at one end of the shaft.

While it is understood that this drive and clutch may be used for various purposes, it is particularly adapted to fulfil such function in a calculating machine. The driving element is here shown as a small electric motor which is allowed to run constantly during the period in which the machine is employed. The indicator-bearing shaft is subjected to a constant torque imparted thereto by the power of the driving element communicated through several rotating instrumentalities carried by, and in constant frictional engagement with, a disk upon the shaft. A detent is operable to prevent shaft rotation and is releasable to permit its free rotation due to the mentioned frictional engagement.

In the preferred embodiment as disclosed in the first three figures of the accompanying drawings, the novel means for imparting a constant torque to the shaft 2, is shown as borne on the shaft end outside of the casing 1. Such novel means includes a disk 6 having a hub 7 mounted upon a sleeve 8 carried by the end portion of the shaft 2. A set-screw 9, passed through apertures in the hub 7 and sleeve 8 and spotted, as at 10, in the shaft 2, functions to retain the disk on the shaft 2 and rotatable therewith. The instrumentalities frictionally actuating the disk are shown as rotatable devices such as flanged pulleys 11. The plurality of bearings on the disk 6 for these pulleys 11 is provided in this embodiment by means of the studs 12. These studs are similar and each has a reduced screw-threaded portion 13 received in threaded engagement with an aperture in the disk 6. Their heads may each be provided with a slot 19 to afford a facile means for their positioning by means of a screw driver. A smooth annular bearing surface 14 is provided on each stud and carried thereon is a bushing 15 upon which is mounted the pulley 11. The outer flange 16 of the stud 12 effectually prevents dis-

placement of the bushing 15 which at its inner side is similarly prevented by the face of the disk 6. While any material or substance having the requisite qualities may be employed for such bushing, it is found that what is known in the art as arguta wood functions efficiently for this purpose. Such material is usually a rock maple or similar wood treated with an oily wax or like substance and is commonly employed for self-lubricating bearings. And while the self-lubricating bushings are shown and described as one means for securing the desired modicum of friction between the pulleys 11 and their studs 12, it is to be understood that any construction is available to embody the invention in which the desired modicum of friction and lubrication are obtained.

These pulleys are actuatable by means of an endless flexible connection which functions to transmit the power of the driving unit, here shown as an electric motor 42. Such connection advantageously employed is belting 17. This belting engages, as shown, several of the pulleys. And, while any suitable number of pulleys may be employed, it is found that seven of them work advantageously. A second such connection, such as a belt 18, engages the periphery of each pulley 11 and functions to cause them all to be actuated upon the rotation of one. Such provision functions to make available the cumulative drag or frictional resistance of all of the pulleys; whereas, were it not employed, two pulleys, as shown in Fig. 1, would not aid in rotating the disk when it is first released. While the arguta wood bushings afford sufficient lubrication so that the pulleys may idly rotate with a modicum of friction, they provide sufficient resistance to the rotation of the pulleys, constantly driven during the use of the machine, so that a moment of forces tending to produce rotation is constantly acting upon the disk 6 and hence this torque is likewise imparted to the shaft 2 with which the disk is rotatable and to which it is affixed.

A stop or clutch member is interposed, upon the shaft 2, between the drive and the meter comprising the usual index wheels which are not necessary to be shown. The function of this stop-motion or detent is normally to hold the shaft 2 against revolution. It is so constructed that revolution of the shaft, under the torque, may readily be permitted as desired. To this end, a disk 20 is mounted upon the shaft 2 and is held revoluble with the shaft by the pin 21. An arm 22 is secured by the screw 23 to the face of this disk which is toward the drive end of the shaft. This arm has a terminally offset portion 24 which is normally engaged by a stop which prevents movement of the disk. This stop member or detent is mov-

able to release the disk arm by means of a system of levers actuated by the usual adding bar of the calculating machine. A set of levers to control the release of the clutch disk is shown in the drawings though obviously they may be of any type effecting the desired disk-controlling function. In the embodiment here illustrated, the arm 25 is pivotally mounted on the casing. The lower end of this arm is preferably forked, having two lateral arms terminally offset and forming the shoulders 26. In normal position the shoulder adjacent the disk projects within the path of traverse of the arm 22 and prevents movement of the disk and shaft. The end portion 27 of a bell crank lever, similarly pivotally mounted is received between the two shoulders 26. A spring 28, secured to the opposite arm 29 of the bell crank lever and to the casing 1, normally tends upwardly to push this arm 29 and hence inwardly to hold the shoulder 26 in the path of the offset portion 24 of the disk arm 22. The usual adding bar 30 on the front of the calculating machine is mounted so that, upon its manual depression, its boss 31 will depress the arm 32 of a pivoted bell crank lever. The arm 33 of such lever, contacting with the arm 29 will depress the latter against the tension of the spring 28. Thus, upon the depression of the bar 30, the pivoted arm 25 is withdrawn. In operation the device is simple, efficient, durable and overcomes effectively the disadvantages of the present drive. When it is desired to permit the revolution of the shaft 2 in order to cause the meter or index wheels to function, the adding bar 30 is downwardly pressed. This force transmitted through the lever system effectuates the withdrawal of the shoulder 26 from engagement with the offset portion 24 of the disk arm 22. The disk 20 and shaft 2 are then freely revoluble under the torque constantly imparted to the shaft by the novel driving mechanism herein. The "pick up" or acceleration is certain, rapid and without jar, jump or noise, nor is an electric motor overtaxed by a sudden load, as the load on the power source is substantially constant. When the key-bar is depressed it is immediately released so that the shoulder, under the indirect action of the spring 28, immediately resumes its place in the path of the portion 24 of the disk arm. The revolution of the shaft having been completed, the further movement is arrested by the engagement of the disk arm and the detent. The stoppage of the shaft is certain and without rebound or back-lash as the turning movement is still applied to the shaft and holds the shaft immovably with the disk arm against the detent or stop. Should any part of the mechanism become jammed it is obvious that, when resistance to shaft revolution

passes a predetermined point, the shaft may rest immovable and injury to the parts avoided. In this selected embodiment, the power source here indicated as a small electric motor 42, is provided with a novel 70 mounting. Due to the nature of this new drive, it has been found advisable to provide means which automatically take up slack or compensate for any belting variations. To this end, a bracket 34 is secured to the casing 75 1, though obviously it may be formed integral therewith if desired. The motor support is formed with an arm 35 which is pivotally secured to the bracket 34 by means of the pivot pin 36 passed through bracket 80 and arm. The casing 1 is further provided with a resilient means which yieldably bears this driving element whereby relative movement of the motor and casing is permitted and transmission variations are automatically compensated. Such resilient means in this embodiment comprises metallic spring members, one leaf spring 37 only being shown herein as necessary to achieve this function. This spring 37 is secured to the 85 casing 1 at one end and is preferably upwardly curved to present a base portion upon which the motor rests. The weight of the motor tends to cause it to gravitate in an arc about the pivot pin 36 as a center. 90 The position and resilient qualities of the spring 37 are such that the motor assumes such a position that the weight of the motor is partially counterbalanced by the spring while the remainder of the weight is taken 95 up by affording the requisite tautness to the belt 17. The motor is thus yieldably mounted automatically to compensate for variations in belt adjustment. In Fig. 4 there has been disclosed a modification of the drive employed. Therein, the 100 secondary or pulley belt 18 is dispensed with and the belting 17 contacts directly with the peripheral surfaces of the pulleys 11 instead of contacting with the outer face 110 of the belt 18. In the modification shown in Fig. 5, the secondary belt 18 is similarly not employed. Herein, the two pulleys 39 and 40 bear a fixed relation to the disk 6, being 115 without the bushing 15, as there shown. In the embodiment of the invention disclosed in this application the rotation of the disk 6 is always arrested by the detent at the same point. This is obvious from a glance at the structure disclosed in Fig. 3 which shows 120 that the offset portion 24 is always stopped by the shoulder 26 at the same peripheral point. Hence, the instrumentalities which are positioned on the disk 6 at the space opposite the power source are out of contact 125 with the belt when the disk is detained. The two fixed pulleys 39 and 40 are positioned at such space in this embodiment. They are mounted without relative movement with respect to the disk 6 and there- 130

fore, when the disk is released, they function because of their non-rotatability more positively and quickly to transmit the torque of the belting motion to the disk 6. The number of instrumentalities, so fixed and so functioning, will vary with the number employed on the disk, and, in the embodiment here shown, the disk is provided with five rotatable and two non-rotatable pulleys.

10 It is to be understood that the construction disclosed herein is illustrative but not restrictive and that the same may be modified within the meaning and scope of the claims which follow.

15 Having fully described our invention, what we claim as new and desire to secure by Letters Patent is:

1. A driving mechanism comprising a driving element, a driven member, a flexible, 20 endless transmission device connecting said element and said member, means preventing rotation of the driven member and operable to permit the same, and movable means on the driven member actuated by said transmission to impart constant torque to said member whereby it is rotated when permitted by said preventing means.

2. A driving mechanism comprising a driving element, a rotatable driven member, a 30 flexible, endless transmission device connecting said element and said member, means preventing rotation of the driven member and operable to permit the same, rotatable means on said rotatable driven member, actuated by the transmission device, and having resistance to rotation sufficient to cause the driven member to rotate when permitted by said preventing means.

3. A driving mechanism comprising a driving element, a rotatable driven member, a flexible, endless transmission device connecting said element and said member, a detent to prevent rotation of the driven member and operable to permit the same, a plurality 45 of rotatable instrumentalities on said driven member, a bearing on said driven member for each instrumentality, said instrumentalities being rotated by said transmission device and functioning to transmit torque to the driven member whereby said member is rotated when permitted by said detent.

4. A driving mechanism comprising a driving element, a rotatable driven member, a flexible, endless transmission device connecting said element and said member, a detent to prevent rotation of the driven member and operable to permit the same, a plurality 55 of rotatable instrumentalities on said member, said device functioning to actuate said rotatable instrumentalities, a bearing on said driven member for each rotatable instrumentality affording a modicum of friction to each, and means causing all of said instrumentalities to rotate together thereby 60 causing the cumulative friction to impart a

constant torque to the driven member whereby it is rotated under its load when permitted by said detent.

5. A driving mechanism comprising a driving element, a rotatable driven member, a 70 flexible endless transmission connecting said element and said member and functioning yieldably to drive the member, a detent to prevent rotation of the driven member and operable to permit the same, a support for 75 the driven member, pivotal means for securing the driving element to said support, and tension means supporting the driving element whereby compensation is automatically afforded for transmission variations. 80

6. A driving mechanism comprising a driving element, a rotatable driven member, a flexible endless transmission connecting said driving element and said member and functioning to drive the member, a detent to prevent rotation of the member and operable to permit the same, a support for 85 the driven member, pivotal means on said support to secure the driving element thereto, resilient means carried by said support 90 yieldably to bear a portion of the weight of the driving element whereby the other portion thereof automatically maintains the adjustment of the transmission.

7. A driving mechanism comprising a 95 driving element, a rotatable driven disk, a detent to prevent rotation of the disk and releasable to permit its rotation, a plurality of bearings annularly arranged on said disk, a bushing on each bearing, an instrumentality 100 rotatably mounted on each bushing, said bushings affording a modicum of resistance to rotation of the instrumentalities whereby upon actuation of the instrumentalities a torque is constantly transmitted to the disk, 105 a transmission connecting said driving element and said instrumentalities, whereby said instrumentalities idly rotate when the disk is detained and upon its release said disk is rotated.

8. A driving instrumentality comprising a driving element, a rotatable driven disk, a detent to prevent rotation of the disk and releasable to permit its rotation, a plurality of bearings annularly arranged on said disk, a bushing on each bearing, an instrumentality 115 rotatably mounted on each bearing, said bushings affording a modicum of resistance to rotation of the instrumentalities, a flexible, endless transmission connecting said 120 driving element and said disk, said transmission engaging a number of said instrumentalities at one time, flexible endless means engaging all said instrumentalities whereby, upon the actuation of some, the resistance of all is available to cause rotation of said disk when released by the detent.

9. A driving instrumentality comprising a driving element, a rotatable driven disk, a detent to prevent rotation of the disk and re- 125 130

- leasable to permit its rotation, a plurality of bearings annularly arranged on said disk, an instrumentality rotatably mounted on each bearing, said bearings affording a modicum of resistance to rotation of the instrumentalities, flexible endless transmission connecting said driving element and said disk, said transmission engaging a number of said instrumentalities at one time, flexible endless means engaging all said instrumentalities whereby, upon the actuation of some, the resistance of all is available to cause rotation of said disk when released by the detent.
10. A driving instrumentality comprising a driving element, a rotatable driven disk, a detent to prevent rotation of the disk and releasable to permit its rotation, a plurality of bearings annularly arranged on said disk, a pulley rotatably mounted on each bearing, said bearings affording a modicum of resistance to rotation of the pulleys, an endless belt actuated by the driving element and engaging a number of the pulleys at one time, an endless belt engaging all the pulleys whereby, upon the actuation of some, 25 the resistance of all is available to cause rotation of said disk when released by the detent.
15. A driving mechanism comprising a driving element, a rotatable driven member, a flexible, endless transmission device connecting said element and said member, a detent to prevent rotation of the driven member and operable to permit the same, a plurality of self-lubricating bearings mounted on said driven member, and a rotatable instrumentality mounted on each of said bearings, said transmission device idly rotating said instrumentalities when the driven member is detained and maintaining a torque upon said driven member whereby the driven member is rotated when permitted by the detent. 35
- In testimony whereof, we have signed our names to this specification.

CHRISTIAN NIELSEN.
CHESTER IRA BABCOCK.
